Archibald Hugh Duncan

Attorney

UNITED STATES PATENT OFFICE.

ARCHIBALD HUGH DUNCAN, OF NAPANEE, ONTARIO, CANADA.

WRENCH.

Application filed February 13, 1922. Serial No. 536,104.

To all whom it may concern:

Be it known that I, ARCHIBALD HUGH DUNCAN, a subject of the King of England, residing at Napanee, in the county of Lennox and Addington and Province of Ontario, Dominion of Canada, have invented certain new and useful Improvements in Wrenches, of which the following is a specification, reference being had therein to the accompanying drawing.

This invention relates to wrenches wherein fixed and movable jaws are held in adjusted position by pawl and ratchet mechanism, and its object is to provide a construction and arrangement whereby the adjustment of the jaws and the application of the wrench to a nut may be quickly accomplished by the operator grasping the wrench and operating the same with one hand.

A further object is to secure maximum rigidity of the jaws and to provide an arrangement of the pawls whereby the movable jaw will be locked against movement and will withstand any strain, for which the body of the wrench is designed, without slippage or liability of breakage.

A further object is to provide a wrench of the character described which will present a very neat appearance and a smooth exterior having no projecting portions liable to interfere with the application of the wrench to the work or to the operation of the wrench.

It is also an object of the invention to provide a very strong compact construction which is cheap to manufacture and has certain other new and useful features herein-after more fully set forth.

With the above and other ends in view, the invention consists in the matters hereinafter set forth and more particularly pointed out in the appended claim, reference being had to the accompanying drawing in which—

Figure 1 is a side elevation of a wrench illustrative of the invention;

Fig. 2 is an edge elevation of the same; and

Fig. 3 is an enlarged cross sectional detail of a portion of the wrench.

As shown in the drawing, 1 indicates a body or stem of the wrench which is preferably a substantially steel bar of greater width than thickness and rectangular in cross section, one end of this bar or body forming the handle portion 2 of the wrench

and the opposite end of the bar being offset laterally to form the fixed jaw 3 of the wrench. Sleeved upon this bar or body 1 is a sleeve 4 which in cross section is of substantially rectangular form and fits closely the bar 1 sliding freely thereon. This sleeve is formed with a laterally offset portion forming the movable jaw 5 of the wrench. The sleeve is also formed with longitudinally extending portions forming ears 6 and 7 at the back and front edges of the body, and pivoted between these ears 7 are suitable pawls 8 and 9 lying adjacent the side faces of the body 1 and preferably of a width equal to that of the body. Pins 10 passing through openings in the ears 7 and openings in the pawls, pivotally attach these pawls intermediate their ends to the ears and each pawl is curved on its outer side longitudinally of the body and, as shown, may be knurled to provide an efficient finger hold so that these pawls may be readily turned upon their pivots against the action of the springs 11 comprising spring wires which are securely fixed at one end within holes bored longitudinally inward from one end of the sleeve with their free ends in contact with the inner sides of the tail portions of the dogs 8 and 9. The opposite or lower ends of the dogs are sharpened or suitably formed to engage a series of notches in opposite sides of the body 1, said notches forming between them ratchet teeth 12 over which the dogs slip as the movable jaw is slid along the body toward the fixed jaw. Preferably, the ratchet teeth 12 at one side of the body are in staggered relation to that of the opposite side of the body so that, as clearly illustrated in Fig. 3, only one of the pawls will be seated in a notch and the other pawl will be half way up the incline of the tooth at the other side of the body, thus providing a very fine adjustment of the movable jaw without the necessity for making the ratchet teeth so fine that there would be liability of slippage when heavy strain is applied to the wrench.

As the pawls engage the sides of the body, and as they are of substantially the full width of the body, a very secure hold on the body is provided and the strain is taken by the pawl in a transverse direction, thus insuring against slippage and at the same time relieving the pivots of these pawls from much of the strain which would otherwise come directly thereon.

Further, the arrangement of the pawls at the sides of the body permit the operator in grasping the wrench to apply the same to a nut, to at the same time grasp the pawls 5 in a convenient manner for compressing or deflecting the springs 11 and thus releasing the dogs from engagement with the ratchet teeth. The operator may therefore, with one hand, conveniently operate this 10 wrench, sliding the movable jaw up into firm contact with the nut as he applies the wrench to the nut. As the dogs are of substantially the same width as the body of the wrench, ample surface is provided so 15 that the operator's fingers will readily engage and operate the dogs, and as these outer surfaces of the dogs are curved in the direction of the length of the body, a smooth rounded exterior is presented and 20 as the springs 11 are located entirely beneath the dogs, there are no external projections upon the wrench to interfere with its application to the work or to catch and interfere with the operation.

25 The particular arrangement of the dogs lends such strength thereto that they will hold the movable jaw without slippage regardless of the strain put upon the wrench. A very compact arrangement is secured 30 which presents a neat appearance and is cheap to manufacture, and while a specific embodiment of this invention has been shown in the accompanying drawing, it will be understood that changes within the scope 35 of the appended claim have been contem-

plated and that I do not, therefore, limit myself to the particular form shown.

Having thus fully described my invention, what I claim is:—

A wrench wherein a body of rectangular form in cross section is provided, said body being of extended width relative to thickness to provide wide side faces and narrow front and back edges, said body being formed with an integral jaw portion projecting laterally from the front edge of said body, and a movable jaw opposing the fixed jaw and having a sleeve portion sleeved upon said body to slide longitudinally thereon, said wrench being characterized in that said wide side faces are formed with teeth extending transversely of said faces and parallel with the longitudinal plane of said jaws, and pawls pivotally connected to said sleeve of said movable jaw to swing toward said wide side faces of the body into engagement with said teeth, said pawls having wide end portions to engage said teeth and to have a bearing thereon throughout the width of said side faces of said body, and said teeth and pawls being relatively positioned in such manner that active pawl engagement during service is limited to a single pawl.

In testimony whereof I affix my signature in presence of two witnesses.

ARCHIBALD HUGH DUNCAN.
